UNITED STATES PATENT OFFICE.

GEORGE E. ROLLINS, OF BROCKTON, MASSACHUSETTS.

PLUG FOR RUBBER TREADS.

1,217,881.

Specification of Letters Patent. Patented Feb. 27, 1917.

Application filed May 1, 1916. Serial No. 94,547.

To all whom it may concern:

Be it known that I, GEORGE E. ROLLINS, a citizen of the United States, residing at Brockton, in the county of Plymouth, in the 5 State of Massachusetts, have invented a certain new and useful Improvement in Plugs for Rubber Treads, of which the following is a specification, reference being had to the accompanying drawings.

10 This invention relates to treads, and is more especially concerned with that class of treads such as soles and heels of footwear, in which plugs are inserted or otherwise built into the treads, in order to increase the 15 tractive and wearing qualities, and the general efficiency of such treads. My present invention relates more particularly to means for so anchoring the plug or plugs in the tread that it shall be impossible for them 20 to become loosened in, or separated from, the tread in ordinary use, or even by accident.

My invention will be best understood by reference to the following description, when 25 taken in connection with the accompanying drawings showing two specific embodiments thereof, while its scope will be more particularly pointed out in the appended claims.

30 In the drawings:

Figure 1 is a bottom plan of a tread member in the form of a shoe sole and heel having plugs embodying my invention secured in the heel.

35 Fig. 2 is a vertical sectional view on an enlarged scale on line 2-2 of Fig. 1; and

Fig. 3 is a relatively enlarged central vertical sectional view of an improved form of plug embodying my invention.

40 Referring to the drawings, and to both embodiments of my invention which I have selected for illustration, I have there shown a tread member *a* in the form of a shoe heel, the same being made preferably of vulcanized rubber. In this tread member is embedded a wear-resisting member *b*, which may be of solid rubber, as illustrated in Fig. 3, or of rubberized fabric coiled upon itself, as in Figs. 1 and 2. This wear-resisting 45 member has a portion presented at the tread surface to receive the wear and to increase the tractive qualities of the tread. The wear-resisting member has another contigu-

ous portion, herein a lateral surface, contacting with the tread member *a*, as clearly 55 shown in Fig. 2, thus providing a direct union between these two parts.

As a means for anchoring the wear-resisting member in the tread member, I have herein provided suitable means, including 60 a metallic anchor member *c*, preferably of cupped disk form, as best seen in Fig. 3. In both forms, the cup is of such size that the plug proper, or wear-resisting member fits tightly therein. The annular rim of the 65 cup projects laterally from the wear-resisting member, and is laterally interposed between the latter and the tread member, but preferably does not extend to the tread surface. By terminating it short of the tread 70 surface, the cup is prevented from striking floors and pavements. If the cup were to strike, it would produce an unpleasant noise, floors, rugs and carpets would be apt to be injured, and the cup itself would be likely 75 to be distorted and injured. Still other advantages will readily suggest themselves.

As a further means for anchoring the plug in the tread member, it may be provided with suitable lateral projections, herein 80 in the form of a dowel pin *d*, which is passed through the annular walls of the cup *c*, as best shown in Fig. 3, this arrangement being also indicated in Fig. 2. The 85 projecting ends of the dowel pin laterally interengage with the tread member intermediate the upper and lower surfaces of the latter, which, by the way, it is to be observed, is herein formed as one piece, and by this means the plug is permanently 90 united with the tread member, and is locked against movement in all directions. The intermediate portion of the dowel pin passes through the plug proper, or wear-resisting member *b*, and interlocks therewith, thus 95 effectually locking the latter against movement in all directions. Thus, it is apparent that, even though the plug should by any chance become loosened in the tread member, it cannot escape because it is interlocked therewith and held against movement in either direction. As an additional means for securing the plug, I prefer to provide openings in the bottom of the cup, as shown in Figs. 2 and 3, in order that the 100 rubber of the tread member may flow into 105

and through said openings, and become vulcanized to the plug.

By preference, I form the plug *b* with one or more radial ribs *b'*, which are thus adapted to be seated in corresponding notches in the rim of the cup *c*, to aid in preventing the rotation of the plug in the cup, as will be evident from an inspection of Figs. 1 and 2. It will be evident that, in the form shown in Fig. 2, and where the rim of the cup is notched, the ribs actually project through these notches into direct contact with the tread member in the plane of the cup rim. This will be clearly apparent from an inspection of Fig. 2, when it is considered that the plane of the section line 2-2 passes through the ribs.

As a still further means for securing the plug in the tread member, by preference, I provide a hard rubber tubular core *g* in the center of the plug *b* (see Figs. 1 and 2), the central opening of which core is somewhat smaller than the head of a nail *h*, driven through the core and the cup into the tread member, as will be understood by reference to Fig. 2 of the drawings. As the nail is thus driven through the core, the nail head forcibly expands the core, and the latter in tending to contract after the passage of the nail head, effectually locks the nail against accidental misplacement or withdrawal. This construction also conceals the nail from view, and avoids disfiguring the more or less ornamental surface of the tread member.

Any desired number of plugs may be located in the heel, and they may also be provided in the sole of the shoe if desired. The plugs may be cheaply produced, and when anchored as I have described in detail, it is impossible to remove them from the tread member without actually cutting the rubber of the latter away from the plugs, since the latter are permanently interlocked with the tread member.

In the operation of making my described plugs, the plug proper, or wear-resisting member *b*, is seated in the cup or anchor member *c*, and is suitably secured therein, as by means of the dowel pin. The structure thus provided is then suitably located in the mold in which the tread member is to be formed, and in the operation of vulcanizing the tread member, the plug or plugs are fixedly anchored therein.

While I have herein shown and described two forms or embodiments of my invention for illustrative purposes, and have disclosed and discussed in detail the construction and arrangement incidental to two specific applications thereof, it is to be understood that the invention is limited neither to the mere details or relative arrangement of parts, nor to its specific embodiments herein shown, but that extensive

deviations from the illustrated forms or embodiments of the invention may be made without departing from the principles thereof.

Having thus described two specific embodiments of my invention, what I claim and desire by Letters Patent to secure is:

1. A heel comprising a rubber body member having seated and vulcanized therein, a plug comprising a cup, a wear-resisting member, a dowel-pin locking said member in said cup, and means for anchoring the cup in the heel.

2. In combination with a rubber heel, a plug vulcanized in said heel, said plug comprising a wear-resisting member, a cup adapted to receive said wear-resisting member, and a dowel pin extending through the lateral portions of the cup and wear-resisting member, to lock the plug in the cup.

3. In combination with a rubber heel, a plug vulcanized therein, said plug comprising a wear-resisting member, a cup adapted to receive said wear-resisting member, and a dowel pin extending through the lateral portions of the cup and wear-resisting member; the end portions of the dowel pin being extended beyond the cup, and terminating at each end within the heel.

4. In combination, a one piece resilient tread member having two opposite surfaces one of which is a tread surface, a plug embedded in said member, said plug comprising a wear-resisting member having a portion presented at the tread surface, and locking means extending into said tread member and into said wear-resisting member in the same general direction as said surfaces and laterally interlocking with said tread member and with said wear-resisting member intermediate said opposite surfaces.

5. In combination, a resilient tread member having two opposite surfaces one of which is a tread surface, a plug embedded in said member, said plug comprising a wear-resisting member having a portion presented at the tread surface, and anchoring means consisting of a member having a wall interposed between and directly engaging said tread member and said wear-resisting member and having a part projecting laterally from said wall from opposite sides, respectively, thereof into lateral interlocking engagement with both of said members, thereby to lock said wear-resisting member to said anchoring means and to lock said anchoring means to said tread member.

6. In combination, a resilient tread member having a tread surface, a plug embedded in said member, said plug comprising a wear-resisting member having a portion presented at the tread surface, and fastening means extending into, and inter-

locking with, said wear-resisting member and laterally into and interlocking with said tread member to secure said plug in said tread-member.

7. In combination, a resilient tread member having a tread surface, a plug embedded in said member, said plug com-

prising a wear-resisting member having a portion presented at the tread-surface, and fastening means extending transversely of 10 the sides of said wear-resisting member entirely through the latter and laterally into said tread member.

GEORGE E. ROLLINS.
